BRASSIÈRE

Raymond J. Redares, Los Angeles, Calif.

Application April 16, 1945, Serial No. 588,555

3 Claims. (Cl. 2—42)

1
This invention relates to a brassière. Garments of this character are now in extensive use, and serve primarily to hold the breasts in a well defined dome, thereby lending a pleasing contour to the female figure.

It is one of the objects of this invention to improve, in general, garments of this character.

It is another object of this invention to make it possible to support the brassière firmly upon the bust without imposing any forces upon the breast cups such as would tend to flatten the breasts, or otherwise to produce a distorting pressure thereon.

In order to ensure that these objects may be attained, the materials for the fabrication of the cups and other parts of the article are selected and employed in a definite manner. It is, accordingly, another object of this invention to make it possible, by such means, to utilize relatively fine materials, such as lace, or the like, and yet to ensure that the breasts are adequately supported.

This invention possesses many other advantages, and has other objects which may be more clearly apparent from a consideration of one embodiment of the invention. For this purpose, there is shown a form in the drawings accompanying and forming part of the present specification. This form will now be described in detail, illustrating the general principles of the invention; but it is to be understood that this detailed description is not to be taken in a limiting sense, since the scope of the invention is best defined by the appended claims.

Referring to the drawings:

Figure 1 is a front elevation of a brassière incorporating the invention as it would appear when extended on a flat surface;

Fig. 2 is a pictorial representation of the brassière illustrated in Fig. 1 shown on a wearer; and

Figs. 3 and 4 are developments of the two layers of fabric which are used for forming the breast cups.

The garment is intended to encircle the body of the wearer and to provide a pair of breast cups 1 and 2 for supporting the breasts of the wearer. Along the outside edge of each cup, as well as at the bottom edge thereof, a body-encircling member is formed which is made of several fabric parts, now to be described.

Thus, between the cups 1 and 2 there is disposed an elastic gore 3 having its apex disposed in the concavity formed by the lower edges of the cups 1 and 2. The gore preferably has a one-way

stretch in a horizontal direction. The converging upper edges of the gore 3 are appropriately stitched to the lower edges of the cups 1 and 2. The sides of the gore are likewise appropriately stitched to the inelastic stout fabric members 4 and 5 disposed immediately below the cups 1 and 2. The material for members 4 and 5 may be doubled; and the upper edges are stitched to the lower edges of the cups 1 and 2.

10 To complete the body-encircling member, wedge-shaped members 6 and 7 are provided having concave edges stitched respectively to the outer edges of the cups 1 and 2. These members 6 and 7 are likewise preferably formed of a stout 15 inelastic member. Preferably, the lower edges of the members 6 and 7 are reinforced by a band or tape 8, 9 disposed on the inner side of the members 6 and 1. This reinforcement serves to maintain the brassière in place on the figure 20 without rolling up.

At the extremity of one of the members, such as member 6, for example, a hook-like member 10 may be provided, supported by the loop of elastic webbing 11 attached to the member 6. 25 The hook-like member 10 is adapted to cooperate with the loop 12 attached to the extremity of the member 7, and also preferably made of elastic material.

It is to be noted that, when the brassière is laid out on a surface, as shown in Fig. 1, the lower edges of members 6 and 7 form an arch. Due to this type of construction, the brassière is prevented from pulling upwardly along the back of the wearer.

30 35 The structure of the cups 1 and 2 is important, and will now be described in detail.

The cups 1 and 2 may be formed either of a single strong fabric, or a double layer of fabric, such as lace.

40 45 In the double layer structure, the top layer is illustrated in developed form in Fig. 3 by reference character 13; and the lower layer is similarly illustrated in developed form in Fig. 4 by the reference character 14. The two layers are intended to be joined by embroidery chain stitching 15, indicated in Fig. 1, and which is run to form a so-called "vermicelli" design. The stitching 15 forms a series of convolutions of haphazard design. These convolutions are fairly closely spaced. The stitching assures that the stresses imposed on the cup layers 13 and 14 will be equalized between them; yet, due to the convolutions, there is no fixed direction that can restrain the fabric too greatly from accommodating the cup to the

stresses imposed upon the cup when the garment is worn.

In order further to obtain the advantages of the invention, the direction of the threads in the cup layers must be considered. In Figs. 3 and 4, the line 28 represents the middle front of the garment, where the two cups 1 and 2 are joined. In the top layer 13 the threads running parallel to the selvage of the material have a direction indicated by the arrow 16. As the dome is formed by bringing the two edges 17 and 18 together, the threads at the outer edge of the cup are conformed to the dome. There is a bias at the top of the cup which permits this part of the cup to stretch in the direction of arrow 19; that is, the bias is in this direction.

Similarly, the threads running parallel to the selvage edge in the lower layer 14 (Fig. 4) are in the position indicated by the arrow 20. However, at the upper portion of the breast cup, there is a bias, permitting stretching along the direction of arrow 21.

The directions of the selvage edges of the two layers 13 and 14 are chosen purposely, so that they are at right angles to each other, as represented by the arrows 16 and 20. In fine materials, such as lace or net, there is a difference in the strength of the warp and woof threads; accordingly, by making the direction of the selvage edge different between the layers, a more uniformly strong structure is provided for the cups.

Furthermore, the lower edge 29 of the cup 1 has a direction substantially along the direction of either the warp or woof threads.

The effect of this arrangement is that any force exerted along the lower edges of the cups by the body-encircling band is ineffective to distort the cups. At the same time, the upper portion of the cups can readily conform themselves to the contour of the wearer, since the shoulder strap 24 or 25 exerts a force diagonal of the direction of the threads. The vermicelli embroidery reinforces the cups, and especially by joining the layers 13 and 14 securely together. In this way, both layers equally divide any stresses upon the fabric of the cups. Accordingly, the cup layers 13 and 14 need not be made of stout material, as sufficient strength is obtained by the joined layers.

Reinforcement for at least some of the cup edges is provided by the stout inelastic fabric members 22 and 23. The member 22 is attached over the top of edges 30, 31 of cup 1, and crosses so that it extends substantially to the lowermost point of cup 2. Similarly, the member 23 crosses underneath member 22 to reinforce the top of cup 2 and the lower portion of cup 1. These members 22 and 23 are permanently stitched to the cups along their entire length; and they are also stitched together where they cross. Thus, they form a frame or margin for both cups along the edges corresponding to lines 29, 30, and 31 of Figs. 3 and 4. Furthermore, these reinforcing members are preferably of strong ribbed material, one series of threads of which run in a substantially vertical direction. Shoulder straps 24 and 25 are joined to the tops of the cups by the aid of loops 26, 27. At their other ends they are fastened adjacent the extremities of the body-forming members 6 and 7.

Accordingly, since the shoulder straps 24 and 25 exert an upward pull upon the members 22 and 23, these members are capable of transmitting the pull without being urged out of place; for

the pull is in the direction of one of the series of threads in these members.

At the same time, the shoulder straps 24 and 25, exerting a pull on the lower edges of breast cups 1 and 2, serve to maintain these edges flat and against the body of the wearer. This effect is due to the crossing over of the reinforcing members 22 and 23.

It is not essential that the cups 1 and 2 be formed of double layers. A single layer can be used if it is of sufficiently stout material. In such event, the threads parallel to the selvage edge may be arranged as in either of the layers 13 or 14 (Figs. 3 and 4).

The inventor claims:

1. In a garment of the character described: a body-encircling member; a pair of breast cups attached to the member; each of said cups being formed of a fabric in which the threads at least at the upper portions of the cups are diagonal to the direction of pull on the cups when in use; a pair of inelastic reinforcing bands, each extending along and attached to the top edge of the respective cup, and crossing at the center of the garment to extend along a portion of the lower edge of the other cup to a place substantially below the crest of the said cup, said bands being permanently attached together where they cross; and shoulder straps connecting the reinforced upper edges of the breast cups and encircling members, the straps and the bands being thereby coordinated to hold the breast cups against the body of the wearer.

2. In a garment of the character described: a body-encircling member; a pair of breast cups attached to the member, each of said cups being formed of two layers of thin fabric stitched together along lines that permit the cups to conform to the breasts, the respective warp threads of the layers being at substantially right angles to each other; reinforcements at the top edges of the cups; and shoulder straps connecting the reinforced upper edges of the breast cups and encircling members.

3. In a garment of the character described: separate body-encircling members; a pair of breast cups attached to said members, each of said cups being made of superimposed layers of thin fabric lightly stitched together, the respective selvage edges of each layer being at substantially right angles to each other; an elastic gore connecting the encircling members and disposed in the concavity formed by the lower inner edges of the cups; crossed reinforcing members attached respectively to each breast cup, and to each other, for coordinating the flexing movement of the breast cups; and shoulder straps connecting the reinforced upper edges of the breast cups and the encircling members.
